UNITED STATES PATENT OFFICE.

FRANK MCINTYRE, OF NEW YORK, N. Y., ASSIGNOR TO THE EAGLE PENCIL COMPANY, OF SAME PLACE.

COMBINATION-INSTRUMENT.

SPECIFICATION forming part of Letters Patent No. 378,261, dated February 21, 1883.

Application filed November 30, 1887. Serial No. 256,581. (No model.)

To all whom it may concern:

Be it known that I, FRANK MCINTYRE, a resident of New York city, in the State of New York, have invented certain new and useful 5 Improvements in Combination-Instruments, of which the following is a specification.

My present invention has relation to that general type of combination-instruments illustrated in Letters Patent No. 273,232, of February 27, 1883--viz., an instrument in which is comprised a divided sheath or handle having its parts longitudinally movable with respect to each other, and distinct grasping mechanisms—one for each part of the handle—connected together, and each adapted to engage the device or article to be contained in its part of the handle, in combination with retracting-spring mechanism which normally holds the parts of the sheath in a position in which the 20 grasping mechanisms will engage the device to be held by them.

The nature of my improvement and the manner in which the same is or may be carried into effect can best be explained by reference 25 to the accompanying drawings, in which—

Figure 1 is a longitudinal central section, partly in elevation, of the instrument with the pen-holder protruding from its end of the sheath. Fig. 2 is a like sectional elevation 30 representing the lead projecting from its end of the sheath while the pen-holder is drawn back. Fig. 3 is a perspective view of the instrument with both lead and pen holder retracted.

It will be understood that the devices or articles to be held or contained in the sheath 35 may be of any desired kind. For the purposes of illustration I have in the present instance provided a pencil or pencil-lead and a pen-holder, each to project from its own end of the sheath. The grasping mechanism for the lead is substantially that of the "automatic" pencil, so called, such as set forth in Reissued Letters Patent No. 8,967, of November 18, 1879.

The grasping mechanism for the pen-holder 40 is substantially that of what is now known in the market as the "Arrow" pen-holder, such as set forth in Letters Patent No. 356,996, of February 1, 1887.

A is the sheath or handle. B is the pen-holder, sliding freely within the

handle, and having a tubular stock or shank which fits within the said handle, so as to give steadiness to the pen-holder.

C is the spring-closed cover or stopper for 55 the pen-holder end of the sheath, hinged or loosely jointed to its pusher-rod G, and adapted, when the pen-holder is protruded, to engage a notch, a, in the latter, as seen in Fig. 1, all substantially as described in Letters Patent 60 No. 356,996, above named. The pusher-rod G, however—unlike the correspondingly-named rod in said Letters Patent last referred to—is tubular, and is closed at its end adjoining the cover C, so as to form a 65 lead-receiving tube similar to the longitudinally-movable lead-receiver of the automatic pencil described in Reissue Patent No. 8,967, hereinbefore referred to. The end of this tube G from which the lead is intended to 70 project terminates in spring-expanding clamping-jaws c, similar to the clamping-jaws of an automatic pencil; and these jaws are, by a retracting-spring, (hereinafter described,) normally closed by being drawn against the 75 contracted portion b of the tip T. The tip beyond its contracted portion is expanded into a globular or other suitably-shaped nozzle, T', (perforated for the passage of the lead,) which 80 completely covers and shields the lead-grasping jaws, there being sufficient room within the part T' for the longitudinal movement of the jaws necessary to permit them to move far enough away from the contracted portion or neck b to allow of their expansion and the consequent release of the lead. This feature— 85 viz., the covering of the jaws by the nozzle T'—is a feature which may be applied to the ordinary automatic pencil, as well as to the combination-instrument represented in the 90 drawings, although in the instance last named it has the added advantage of furnishing a convenient knob or pressure button or cap for operating the cover C, as will be hereinafter explained.

I may state here that I am aware that it is 95 not new to provide a covering sleeve or nozzle which completely conceals and covers the jaws, such a device being shown in Letters Patent No. 223,498, of January 18, 1880; but 100 in said patented device the covering sleeve or nozzle is distinct and separate from the tip

which compresses the jaws, whereas in my arrangement no separate sleeve is employed, but the covering-nozzle is merely a prolongation of the compressing-tip.

5 The tip, which in effect forms part of the sheath or case A, is made longitudinally movable with reference to said part A, for the purpose of forming a spring-retracted pressure-cap for operating the cover or stopper C. To 10 this end it fits and is adapted to slide back and forth in a sleeve, D, fixed in the pencil end of the handle A, said sleeve being provided as a convenient receptacle for the coiled spring E, which is confined between a shoulder, d, in 15 the tip and a washer, d', which brings up against an inturned annular flange, e, on the inner end of the sleeve D. This washer d' fits loosely around the tubular rod G, and a projection, f, on said rod G is so placed that when 20 the rod is pushed in a direction to advance the lead-grasping jaws said projection f will bear against and push forward the washer d', thus compressing the spring E. When pressure on the rod G is removed, the spring by its 25 expansion will retract the jaws and draw them again into contact with the contracted neck b of the tip. Now, under this arrangement it will be seen that by pressing inward the tip T against the stress of the spring E the head 30 or nozzle T', by bearing against the jaws, will press forward the rod G, and will thus operate the stopper or cover C and cause it to open. As soon as this pressure is removed from the tip the retracting-spring E at once returns 35 the parts to their normal position.

It remains to describe the manner of operating the jaws in order to cause them to expand, and thus release the lead, which operation is brought about by a longitudinal movement of the tubular rod G in a direction opposite to that in which it moves in opening the stopper C. For this purpose the rod G is jointed not directly to the cover or stopper C, but to a rod, g, which passes through the stopper, and is provided with a presser-cap, h, between the head of which and the opposite end of the interior of the hollow stopper is confined a spiral spring, i, said spring tending to hold the rod g normally retracted outwardly. 45 By pushing the pressure-cap i inwardly it will be caused to push the tubular lead-holding rod G in the direction necessary to permit the lead-holding jaws to expand. As soon as this pressure is removed, the retracting-spring E 50 returns the parts to normal position, the spring i assisting in this action, and also steady ing and assuring the position of the rod and pressure-cap g h.

Having now described my invention and 60 the manner in which the same is or may be carried into effect, I state in conclusion that I do not restrict myself to the exact details hereinbefore described, and represented in the accompanying drawings in illustration of my 65 invention; but

What I claim herein as new and of my own invention is as follows:

1. The combination, with the sheath, the longitudinally-movable lead-containing tube or rod, and the lead-grasping mechanism located at one end of the sheath, of the cover or stopper placed at and adapted to close the opposite end of the sheath and hinged or loosely jointed to said longitudinally-movable lead-containing tube, and the retracting-spring operating to move the said tube in the direction necessary to cause the stopper to close its end of the sheath. 70

2. The combination, with the sheath, the longitudinally-movable lead-containing tube and clamping-jaws, the longitudinally-movable compressing-tip for said jaws, and the retracting-spring, of the freely-sliding pen-holder or other article adapted to project from the end of the sheath opposite to that from 85 which the lead projects, and the cover or stopper hinged or loosely jointed to said lead-containing tube, the combination being and acting substantially as set forth. 80

3. The combination, in an automatic pen-holder, with the sheath, the lead-containing tube, and the lead-grasping jaws, of a jaw-compressing tip provided with a nozzle, T', which covers and conceals said jaws and is perforated for the passage of the lead, substantially as and for the purposes hereinbefore set forth. 90

4. The combination, with the sheath or case and the cover or stopper, of the longitudinally-movable lead-containing tube forming a 100 pusher-rod for said cover or stopper, and the presser-rod mounted and longitudinally movable in said stopper and hinged or loosely jointed to said lead-containing tube, as and for the purposes hereinbefore set forth. 105

5. The combination of the longitudinally-movable lead-containing tube, the sheath, the cover or stopper C, the presser rod and cap mounted and longitudinally movable in said stopper and hinged or loosely jointed to said 110 tube, and the spring i, as and for the purposes hereinbefore set forth. 110

6. The combination of the sheath, the longitudinally-movable lead-containing tube terminating at its outer end in clamping-jaws, 115 the longitudinally-movable jaw-compressing tip or nozzle, the retracting-spring E, the cover or stopper C, the freely-sliding tubular holder for a pen or other article, the longitudinally-movable presser-rod mounted in and carried by the stopper and hinged or loosely jointed to the lead-containing tube, and the spring i, these parts being arranged together 120 for joint operation substantially as and for the purposes hereinbefore set forth. 125

In testimony whereof I have hereunto set my hand this 28th day of November, 1887.

FRANK MCINTYRE.
